UNITED STATES PATENT OFFICE

171,851

FEEDING TRAY

Delbert L. Greenlee, Haven M. Zimmerman, and
Harry B. Greenlee, Dunbar, W. Va.

Application August 31, 1953, Serial No. 26,634

Term of patent 14 years

(Cl. D44—10)

To all whom it may concern:

Be it known that we, Delbert L. Greenlee, Haven M. Zimmerman and Harry B. Greenlee, citizens of the United States of America, residing at Dunbar, in the county of Kanawha and State of West Virginia, have invented a new, original, and ornamental Design for a Feeding Tray, of which the following is a specification, reference being had to the accompanying drawing, forming part thereof.

Figure 1 is a perspective view of a feeding tray, showing our new design.

Figure 2 is a top plan view thereof, and

Figure 3 is a side elevational view of the same.

We claim:

The ornamental design for a feeding tray, as shown.

DELBERT L. GREENLEE.
HAVEN M. ZIMMERMAN.
HARRY B. GREENLEE.
